DEGASIFIER

Robert A. Whitlock, Jr., and James E. Dymond, Rockford, Ill., assignors to Automatic Pump & Softener Corporation, Rockford, Ill., a corporation of Illinois

Application November 15, 1946, Serial No. 709,940

10 Claims. (Cl. 183—2.5)

1

This invention relates to improvements in the degasification of liquids, particularly to an improved method and apparatus for removing dissolved gas in stepwise fashion.

An object of the invention is the provision of a method and means for removing absorbed gas from a liquid without the use of any power source other than the pressure energy in the liquid itself.

In general, the invention contemplates diffusing the liquid into a low pressure area where an initial, partial degasification is caused to take place, venting off the removed gas, and then passing the liquid through a vessel which exposes a large surface area of the liquid to further degasify it, and then venting the gas from the vessel.

Other objects and advantages will become apparent from the following description in connection with the drawings, in which—

Figure 1 is a view of one form of the present invention;

Fig. 2 is a sectional view of Figure 1 taken along line 2—2 showing the perforated nozzle in the aspirator;

Fig. 3 is a sectional view of Figure 1 taken along line 3—3 showing a longitudinal section of the atmospheric air intake;

Fig. 4 is an enlarged fragmentary view of the degasified liquid collector pipe connecting with the outlet, and

Fig. 5 is a sectional view taken longitudinally through the tube and adjacent parts.

Referring now more particularly to the drawings, which show an embodiment adapted particularly for the removal of carbon dioxide from water emerging from an ion exchanger, a vessel 1, containing a bed 2 of coke or other material for the liquid to percolate over, is provided with a liquid inlet 3 and outlet 4 and with an air inlet 6 and outlet 7. The air inlet is provided with a tubular screen 8 which in this instance serves to distribute atmospheric air across the bottom of the bed 2.

The liquid under treatment enters the system under normal water system pressure through a pipe 11, in the example given this pipe being connected to an anion exchanger (not shown) and is directed through an injector comprising a nozzle 12 and a diffuser tube 13. For best results the liquid should pass through the nozzle at twenty-five pounds or more per square inch. In this particular instance the nozzle 12 is provided with a number of relatively small perforations 14 out of which the liquid discharges under relatively high pressure, the individual streams being so

2

arranged as to break up or atomize in close proximity to the nozzle into a spray. This is facilitated by the provision of means for breaking up the stream emerging from the nozzle, one means being, as herein shown, a plurality of pieces of gravel indicated at 10 which causes the water passing through the perforations 14 to assume a swirling motion as it emerges from the nozzle. While we prefer to perforate the nozzle in this manner, other specific nozzle constructions will operate satisfactorily; in general we have found that a nozzle that directs the liquid into diffuser tube 13 of the injector in a high velocity turbulent manner is best for effecting this primary degasification. This high velocity diffusion of fluid into the tube 13 creates a low pressure in a suction conduit 16 through which air is drawn through inlet 6 together with gas released from the liquid in the vessel in the secondary degasification; this latter gas composition is entrained in the fluid entering the diffuser tube 13 and is carried to a separation point, in this instance a T 17 which functions as a primary separation chamber from which the mixture of gases is vented to the atmosphere or to a suitable receiver through vent pipe 18. The partially degasified liquid is directed downward through conduit 19 into the vessel 1. A liquid seal, having a level shown at 21, is provided to prevent the recycling of gas from the diffuser tube 13 through the vessel 1. The level 21 is controlled by adjustment of a valve 22 so the level is below the separator T 17 to permit the separated gases to flow freely out of vent pipe 18, and the diffuser tube 13 is inclined downward slightly in the direction of the T to facilitate drainage. The best results appear to be obtained if the tube 13 is disposed in a vertical position with the nozzle above, but this so increases the height of the device as to render it impractical in most instances. This fluid seal may be maintained in any other suitable manner to give satisfactory results, as for instance, by means of a goose neck incorporated in conduit 19.

In the vessel 1, which acts as a secondary separator, the partially degasified liquid is discharged, through perforated pipe distributor 24, over the bed 2. As it percolates down through the bed, over the outside of the loosely packed pieces of coke, etc., the liquid is thereby spread out in a thin film under reduced pressure in contact with the upwardly moving gas, which in this case is atmospheric air drawn through the inlet 6 by action of the injector. Flow through 55 the vessel is thus countercurrent. The liquid

trickles down through the bed to release substantially the remainder of its absorbed gas and the atmospheric purging air is drawn upward through the bed into conduit 16 to continuously sweep out the released gas. At the bottom the liquid is collected in a perforated pipe collector 26, similar to distributor 24, and discharged through conduit 27 into storage tank 28.

In the embodiment shown in the drawings wherein the tank 1 was 14" in diameter and 60" high, the bed depth was approximately 36", the pipe 13 was 1½" in diameter and 18" long, the water pressure in pipe 11 was sixty pounds per square inch, the perforations 14 were No. 66 drill holes disposed at diverging angles of approximately 5 degrees with the longitudinal centerline of the nozzle and the flow rate of water through the bed was 4.3 gallons per minute foot of cross-sectional area. The effectiveness of the degasification is illustrated by the following figures which have been determined from actual tests: With the inlet water in conduit 11 containing 200 parts per million of absorbed carbon dioxide gas, the water in the liquid seal 21 showed a gas content of 75 P. P. M., after the initial degasification by the aspirator 9; and the water leaving the vessel 1 through conduit 27 shows a final gas content of approximately 5 P. P. M. Attention is directed to the fact that the action of the diffuser is to reduce the pressure in the tank 1 to below atmospheric, and that the reduction in pressure may be controlled by adjusting the usual well known factors. In practice we have produced a vacuum as low as 6 inches of water in the tank 1. This reduction in pressure materially assists in the removal of gas from the liquid and greatly reduces the amount of dissolved air in the effluent water emerging from the tank 1.

It will thus be obvious that the device provides a highly efficient method and apparatus for degasifying liquids which utilize no outside source of power other than the initial pressure energy in the liquid itself. Furthermore, both degasification steps are carried out at substantially atmospheric pressure or less, so that relatively inexpensive low pressure equipment may be employed.

While the specific test results given above are those determined when running the degasifier as a decarbonater, it will be understood that the invention is applicable generally to the effective removal of gases from liquids. Furthermore, while the inlet 6 is illustrated as using atmospheric purging air to sweep the secondarily released gas out of the vessel 1, it will be obvious that other sweeping gases may be employed to better advantage in certain instances, as for example, where the liquid to be degasified is a potentially explosive hydrocarbon or the like which must be kept out of contact with air. The invention also contemplates that in certain cases where the object is the removal of the greatest possible amounts of all gases from the liquid, the sweeping gas inlet 6 may be omitted altogether and the vessel 1 maintained under a suitable vacuum by the aspirator 9. While the vessel 1 has been shown packed with a bed of coke or like particles for the liquid to trickle down over, other modifications of this arrangement may be satisfactorily employed. For example, a series of screens, wood slats, balls, etc. may be used to expose the greatest possible liquid surface area for release of the absorbed gas.

While a particular form of the present inven-

tion has been shown, it will be apparent that minor changes therein will readily suggest themselves to others skilled in the art without departing from the spirit and scope of the invention. Having thus described the invention, what is claimed as new is:

1. In a method of removing a dissolved gas from a liquid: a first step of atomizing said liquid in the form of a fine spray into an environment of a non-condensable gas of composition different from that of the dissolved gas to at least partially remove said dissolved gas; and a subsequent step of trickling the partly degasified liquid over a bed of material in an environment of said gas of different composition to effect substantial further degasification of said liquid.

2. In a method of removing a dissolved gas from a liquid: a step of spraying a stream of said liquid to atomize the liquid and entrain a non-condensable gas of different composition from said dissolved gas into said stream to at least partially effect the removal of said one gas from said liquid; a subsequent step of venting the mixture of gases from said stream and thereafter directing said liquid through a container countercurrent to the flow of said gas of different composition to effect a further substantial removal of said dissolved gas from the liquid.

3. In a method of degasifying a liquid, the steps of: passing a stream of said liquid through an aspirator to cause the aspirator to draw gas of different composition through a bed of solid material and into the stream; venting the gases in said stream from the liquid; and thereafter directing said liquid through said bed in contact with said gas of different composition.

4. In a method of removing a gas from a liquid, the steps of: dispersing a stream of the liquid to entrain a stream of air and to draw the latter through a chamber under sub-atmospheric pressure, the dispersion of said liquid stream and the entrainment of said air stream being effective to remove at least a portion of said gas from the liquid; venting off the removed gas and entrained air; and passing the partly degasified liquid through said chamber in contact with the air stream at sub-atmospheric pressure to further effect the removal of said gas.

5. In apparatus for removing a gas from a liquid, a vessel having a liquid inlet and outlet and having a gas outlet, aspirator means connected to a source of said liquid under pressure for dispersing said liquid to effect a partial degasification thereof, said aspirator means having a suction inlet connected to said vessel gas outlet to withdraw gas therefrom to reduce the pressure in said vessel and entrain it in the dispersed liquid, means for collecting the dispersed partly degasified liquid and venting the gas therefrom, means for conveying the partly degasified liquid to the vessel for passage therethrough to the liquid outlet, and means within said vessel for increasing the surface area of said liquid as it passes therethrough to effect a further degasification thereof, said gas being withdrawn through said gas outlet by said aspirator means.

6. In apparatus for removing a gas from a liquid, a vessel having a liquid inlet and outlet and having a gas inlet and outlet, an aspirator connected to a source of said liquid under pressure for directing said liquid into an initial separator to effect an initial partial degasification thereof, said aspirator having a suction inlet con-

nected to said vessel gas outlet to withdraw gas therefrom and entrain it in the dispersed liquid flowing to the initial separator, said separator having a vent for separating gas from the partially degasified liquid, a conduit connecting the separator with the vessel, said vessel having means therein for spreading said liquid out over an increased surface area in the presence of gas entering said gas inlet to effect a final degasification of the liquid, the gas removed from the liquid in the vessel being swept out of the gas outlet by the gas entering said gas inlet.

7. An apparatus for removing carbon dioxide and other gas from water comprising a vessel having a liquid inlet adjacent the top thereof and a liquid outlet in the lower portion thereof and also having an air inlet in the lower portion of the vessel and a gas outlet in the upper portion thereof, an aspirator connected to a source of water containing said gas under pressure for directing the water into an initial separator to effect partial decarbonation thereof, said aspirator having a suction inlet connected to the gas outlet of said vessel to draw gas upwardly through the vessel from the air inlet and entrain it in the dispersed water flowing from the aspirator, said separator having a vent for the escape of air and gas therefrom, means for connecting the separator with the water inlet of the vessel, said means including a trap for preventing return flow of air to the vessel, and means disposed in the vessel for spreading the water over a wide surface area in counterflow relation with the air entering the air inlet to effect final removal of the gas from the liquid by the air entering the gas inlet.

8. In apparatus for removing a gas from a liquid, a vessel having a liquid inlet and outlet and having a gas inlet and outlet, an aspirator having a plurality of small openings providing communication between a source of said liquid under pressure and a diffuser tube for spraying said liquid in a plurality of streams into said diffuser tube, said aspirator having a suction inlet connected to said vessel gas outlet to draw gas therefrom to reduce the pressure in said vessel and entrain the gas in the spray entering the diffuser tube, the spraying of said liquid being effective to partially degasify said liquid, said diffuser tube discharging into an initial separator effective to collect the partially degasified liquid and vent the gases therefrom, said initial separator having connection with said vessel to convey the partially degasified liquid thereto, said vessel having a bed of material therein for said

liquid to flow over to expose a large surface area of the liquid to gas drawn into the gas inlet and through the bed by the action of said aspirator.

5 9. In apparatus for degasifying a liquid, a vessel having a liquid inlet and outlet and a gas outlet, jet means connected to a source of said liquid under pressure for atomizing said liquid into a relatively lower pressure zone to effect
10 partial removal of the gas therefrom by effervescence, means connecting said low pressure zone to the gas outlet of said vessel to evacuate gas therefrom, a separator for separating the removed gas from the partially degasified liquid,
15 means for venting the gas from said separator, conduit means for thereafter conveying the partially degasified liquid into said vessel to further degasify it, and a liquid seal in said conduit means to prevent the cycling of gas from said
20 liquid inlet to said gas outlet.

10. Apparatus for removing an undesired gas from liquid containing the same comprising a vessel having a liquid inlet and outlet, means connected to a source of said liquid under pressure for atomizing said liquid and suddenly releasing pressure therefrom into an atmosphere of a gas of different composition to cause circulation of the latter gas through the apparatus and effect at least partial removal of said undesired gas from the liquid by effervescence, means for venting said gas of different composition and admixed undesired gas from the apparatus, and means for thereafter directing the partially degasified liquid through the vessel in a direction counterflow to the aforesaid gas of different composition to effect further removal of the undesired gas.
